UNITED STATES PATENT OFFICE

104,342

DESIGN FOR A TUMBLER OR SIMILAR ARTICLE

James E. Duncan, 3rd, and Robert A. May, Washington, Pa., assignors to Duncan & Miller Glass Company, Washington, Pa., a corporation of Pennsylvania

Application December 2, 1936, Serial No. 66,260

Term of patent 7 years

To all whom it may concern:

Be it known that we, James E. Duncan, 3rd, and Robert A. May, both citizens of the United States and residents of Washington, Pennsylvania, have invented a new, original, and ornamental Design for a Tumbler or Similar Article, of which the following is a specification, reference being had to the accompanying drawing forming part thereof.

In the drawing, Figure 1 is a perspective view of a tumbler embodying the new design, and Figure 2 is an elevational view of the tumbler shown in Figure 1.

We claim:

The ornamental design for a tumbler or similar article substantially as shown.

JAMES E. DUNCAN, 3RD.
ROBERT A. MAY.
